IRONING TABLE

Leon H. Cummings, Berlin, Mass.

Application March 4, 1939, Serial No. 259,836

1 Claim. (Cl. 38—120)

This invention relates to ironing tables.

The principal object of my invention is to provide a sturdy, well balanced ironing table of improved construction, which can be erected or closed by the simplest of movements. Another object is to so construct said ironing table that the cost of production and assembly of its parts is low, so that it is within the range of purchase of the ordinary housekeeper. These objects are attained chiefly by using certain special members at certain points in the assembly, as will be pointed out.

The foregoing and other objects which will appear as the nature of the invention is better understood, may be accomplished by a construction, combination and operative arrangement of parts such as is disclosed by the drawing and specification. The nature of the invention is such as to render it susceptible to various changes and modifications, and, therefore, I am not to be limited to said disclosure; but am entitled to all such changes therefrom as fall within the scope of my claim.

In the drawing:

Figure 1 is a side elevational view of my ironing table in erected position, the dot and dash lines indicating the leg members moved towards folded position.

Figure 2 is a bottom view of my ironing table with the legs in folded position.

Figure 3 is an end elevational view of my ironing table in erected position.

Figure 4 is an enlarged detail view, partly in section, to illustrate the position of the cross bar supports when the table is erected.

Figure 5 is an enlarged detail view, partly in section, of the hinge and pin means which movably hold the legs to the table top.

As illustrated, my ironing table has a top or ironing board 10 of well known form, to which is hinged as at 11 a leg member 12 which consists of two parts or legs 12a and 12b, which converge toward their lower or free ends and are united together as at 13. Also hinged as at 15 is another leg member 16 which consists of two parts or legs 16a and 16b, which are spaced apart sufficiently to permit the two legs 12a and 12b of leg member 12 to extend between them, so that the narrower leg member 12 crosses and extends between the sides of the wider leg member 16. There is a definite space 18 in each instance between the outer side surfaces of said leg parts 12a and 12b and the inner side surfaces of said leg parts 16a and 16b as illustrated in Figures 2 and 3 of the drawing. The width of said space 18 is pref-

erably at least equal to the width of an edge of a said leg 12a or 12b at a point where a cross bar support 28, later described, is located.

When my table is in upright position said leg members 12 and 16 are maintained in a predetermined position by means of cross bar supports. One cross bar support 20 is secured as at 21 to the edges 22 of said leg member parts 16a and 16b, so that when said leg members 12 and 16 move to upright position the top edges 23 of leg member parts 12a and 12b will contact with said cross bar 20, thereby preventing movement of said leg member 12 in one direction beyond the said point of contact.

Another cross bar support 24 is secured as at 25 to the opposite edges 26 of said leg member parts 16a and 16b, and when said leg members 12 and 16 are in said upright position said leg member parts 12a and 12b contact with and rest on said cross bar support 24. As illustrated in the drawing, these two cross bar supports 20 and 24 prevent said leg member parts 12a and 12b, when in upright position, from moving either towards closed position or the opposite direction any further unless said leg member 16 is moved also. Likewise, said leg member parts 16a and 16b are prevented from movement in one direction by said cross bar support 20 by reason of contact of said support 24 and said legs 12a and 12b, but not prevented from movement in the opposite direction which is towards closed position. A third cross-bar support 28 is secured as at 29 to the said upper edges 23 of said leg member parts 12a and 12b, and when said two leg members 12 and 16 are in upright position the said edges 26 of said leg member parts 16a and 16b contact said cross bar support 28, and further movement of said leg member 16 to closed position is thereby prevented. This third cross bar support 28 extends across said leg member 12 and beyond to a point overlapping both leg member parts 16a and 16b as illustrated in Figure 3 of the drawing. It is made of wood preferably, and can easily be nailed or otherwise fastened on the leg member parts 12a and 12b. It takes the place of dowel pins or blocks which are commonly used on the outer edges of leg member parts 12a and 12b, and which require extra operations to firmly attach and are not as strong as this cross-bar support 28. This member also makes it possible to amply space the leg member parts 12a and 12b laterally from the leg member parts 16a and 16b, which makes it possible to attach all said leg parts 12a, 12b, 16a and 16b nearer to the longitudinal center of said table 55

top 10, thus providing a more rigidly supported table top. Where blocks or dowel pins are used as described in United States Patents 1,638,347 and 1,824,025, the inside leg parts 12a and 12b have to be so close laterally to the other leg parts 16a and 16b that the leg parts cannot be attached to the top as near the center as in my construction. By being able to fasten the leg parts 12a and 12b nearer to the center of the top they provide a central support that makes the whole ironing table firmer when erected. It will thus be seen that by using a cross bar support 28, which extends across the narrow leg member parts 12a and 12b to and overlapping the wider member parts 16a and 16b so as to contact them when the table is erected, all the functions of blocks or dowel pins are accomplished with less labor in assembling my ironing table, and the table top is more soundly supported.

20 To brace the leg members 12 I provide braces 33, and 35 on and between said legs 16a and 16b. Underneath said table top are two reinforcing pieces 37.

What I claim is:

25 An ironing table comprising a top with two leg structures pivoted thereto in spaced apart relation, one of said leg structures being relatively wide and having side leg elements diverging downward, and the other leg structure being relatively narrow and having side portions converg-

ing downward so that the sides of the narrow leg structure are spaced substantially from the sides of the wide leg structure when the table is erected with said leg structures crossed, the wide leg structure having two cross-bars secured thereto at opposite sides and spaced apart along the length thereof to permit the narrow leg structure to pass therebetween, the upper one of said cross-bars being secured to the lower side of the wide leg structure, and the lower cross-bar being secured to the upper side of said wide leg structure, the narrow leg structure having a further cross-bar secured to the top thereof directly above the locality of intersection of said leg structures and so as to be substantially opposite one of the other cross-bars in a direction widthwise of the wide leg structure and substantially opposite the other cross-bar in a direction widthwise of the narrow leg structure when the table is erected, whereby said leg structures are mutually inter-braced at three triangularly spaced areas at the locality of intersection of said leg structures, the cross-bar secured to the narrow leg structure, having extensions at each end to engage the outer side portions of the wide leg structure at widely spaced apart points whereby further rigidity against twisting and weaving movements is insured for the table when the same is erected.
